UNITED STATES PATENT OFFICE.

HARRY S. PARKS, OF PHILADELPHIA, PENNSYLVANIA, ASSIGNOR TO PNEUMATIC COMPANY, OF NEW YORK, N. Y., A CORPORATION OF MAINE.

WATER-LEVEL-INDICATOR INSTRUMENT.

1,379,716.

Specification of Letters Patent. Patented May 31, 1921.

Application filed August 28, 1919. Serial No. 320,386.

To all whom it may concern:

Be it known that I, HARRY S. PARKS, a citizen of the United States, residing at Philadelphia, in the county of Philadelphia and State of Pennsylvania, have invented 5 new and useful Improvements in Water-Level-Indicator Instruments, of which the following is a specification.

The purpose of the present invention is 10 to provide an instrument which is adapted to be located at a distance from a steam boiler or other container of liquid under pressure, and either at the same level or at a level above or below that of the liquid 15 contents of the boiler, etc., for showing with reference to an index the amount by which the actual present level of liquid in the boiler differs from a given reference level. This instrument is the indicating end of a 20 system which is adapted to transmit, through pipe lines containing liquid, the pressure due to a column of water rising to a height above the boiler water level and being under boiler pressure, and that due 25 to the head of water in the boiler likewise under boiler pressure.

Two pipe lines are provided, one of 30 which is connected with the boiler, so that the pressure acting therein is equal to that of a column of water rising to the actual present level of water in the boiler, plus steam pressure; and the other of which is maintained full of water up to a given height above the normal boiler level, and 35 is under the same steam pressure, whereby the pressure acting inside the last-named pipe is as much greater than that acting in the first pipe as the head of water is higher than the boiler water level. These pipe lines are

40 respectively connected to the lower ends of two indicator tubes, which are joined together at their upper ends and hermetically sealed, containing a body of air or other gas in their communicating portions. Thus the 45 pressure of the trapped air is equal to the boiler pressure plus or minus the difference in head due to whatever amount the indicator may be below or above the boiler level; and the two tubes of the indicator contain 50 water columns which are controlled respectively by the water pressures in the two pipe lines above described, and therefore rise to

respectively different heights, between which the same difference exists as exists between the fixed level previously mentioned and the temporary boiler water level.

The present invention is an improvement 55 on an indicator heretofore devised by me and used in such a system as that just above briefly described. The mode previously disclosed of entrapping air or other gas in the sealed upper part of the indicator was to allow the tubes first to become full of air before turning into them the full pressure of the boiler and of the water in 60 the pipe lines. When the boiler pressure is, however, high, the compression to which the air thus trapped must be brought before its pressure equals that of the boiler may in 65 some cases diminish its volume so much as 70 to bring the levels of the indicating columns so near the upper ends of the indicator tubes that readings may be difficult. Accordingly, the object of this invention is to afford means in connection with such an instrument by 75 which to control the volume of air entrapped in the indicating tubes, and to cause the volume thus entrapped to be great enough, even when pressed to the full boiler pressure, 80 to hold the water columns in the tubes down to a level at which they can be easily seen.

The means by which I prefer to give effect 85 to the object thus stated is that particularly described in the following specification and illustrated in the drawings referred to therein, but other forms embodying my principles may be made within the scope and spirit of the protection secured by the appended claims.

In the drawings:

Figure 1 is an elevation of the instrument as a whole, including the indicating columns, volume container and pipe connections.

Fig. 2 is an elevation, but with parts broken away and shown in section, of the indicating tubes and scale of the instrument.

Fig. 3 is a sectional view of the volume chamber.

Like reference characters indicate the same parts in all of the figures.

Preferably the indicator is contained in a case 1, having a door 2, provided with a

transparent panel 3, and it comprises two column-containing tubes, 4 and 5, which, as a preferred feature of construction are substantially co-axial, that designated 5 being 5 contained in the tube 4, and the latter having a closed upper end, while the former is open at its upper end. Thus there is a communication between the upper ends of the tubes, but such communication is closed and hermetically sealed against escape of entrapped air. At one side of the outer tube is a scale 6, preferably fixed in position, and at the other side is a scale 7, which may be adjusted lengthwise, and is suitably graduated. 10 Preferably the zero mark 8 of this scale represents the position which one of the water columns in the indicator should have when the water in the boiler is at the level prescribed as the normal level; while the 15 other graduations may run up or down from the zero mark in terms of inches or other units of measurement above or below such normal level. There may be, also, on this scale, a graduation 9, representing the maximum level, that is, the level corresponding 20 to that of the column of fixed height.

The case, or frame 1 carrying these tubes and scales is connected to a chamber 10, which I call the volume chamber or container, which, as appears from Fig. 3, is a hollow body. A nipple 11, on the lower end of the case, screws upon the threaded upper end of this volume chamber. The lower end of the chamber is connected to a pipe fitting 35 12, having two passageways 13 and 14, from each of which are two branches, controlled by three-way valves 15 and 16 respectively. The branch 17 from the passage 13 is connected with the pipe line which connects 40 with the boiler, and is subjected to variable pressure, according to the height of water in the boiler; while the branch 18 of the passage 14 is connected to the constant level water leg, that is, the water column which 45 rises to a fixed height above the normal boiler water level. The other branches 19 and 20 respectively are drains. From the passage 13 there runs a pipe 21 through the entire length of the volume chamber to the 50 lower end of the inner tube 5, to which it is connected by a coupling 22 of any suitable sort. As the tubes are made of glass from practical necessity, this connector is preferably a section of rubber tubing. 55 The outer tube is open at its lower end, and it rests at that end upon a packing washer, which is seated on a conformable shoulder 24 in the upper end of the volume chamber. Pressure on the tube to make a 60 tight joint at this place is applied by a screw 25 at the top of the frame, which presses upon a filler 26, having a cushion, preferably of rubber or other soft material, which bears on the closed end of the tube 4.

65 The other passage 14 in the connection 12

is connected to a tube 28, which rises to a given height within the chamber 10, and the length of which may be altered at need.

Prior to putting the instrument into action, it is filled with water up to the level 70 of the top of tube 28 (in case it should have been previously empty), or, if it was previously filled with water, the water is drawn off to the same level, by turning the cock 16 to the drip outlet 20. Both tubes of the indicator and the chamber are now full of air above the level of water which rises to the top of tube 28. Then, upon turning the cocks 15 and 16 to connect the pipe lines with the instrument, the boiler pressure causes 80 water to flow through these pipe lines and the passages 13 and 14 into the volume chamber and the inner and outer indicating tubes respectively. The air previously in the tubes and chamber is compressed into the 85 tubes until its pressure equals the pressure of the boiler, when the indicator is at the same height as boiler level, or is greater or less than the boiler pressure by the amount of the water head when it is respectively 90 below or above the boiler water level.

The object of the volume chamber, of course, is to provide so large a volume of air that, when thus compressed, it will hold back the water columns in the indicating 95 tubes a great enough distance below the tops of these tubes for the levels in such columns to be seen through the transparent pane of the door, and preferably, also, as nearly as possible midway between the upper and 100 lower ends thereof; but, as instruments of the same size and volume capacity are adapted for use with different boilers, carrying very different pressures, it is evident that the position of the water column heads 105 will vary according to the boiler pressure unless compensating means are provided. Such compensating means are embodied here in the tube 28, which allows a part of the volume chamber to be occupied by water 110 prior to turning on the pressure, and the length of which may be varied according to the working boiler pressure. For shortening the tube, it is only necessary to cut off 115 its upper end. This can be done readily 120 enough after first unscrewing the fitting 12 from the volume chamber. Then the proportion of the volume chamber occupied in the first place by water becomes less, and it is then possible to apply a higher boiler 125 pressure without raising the indicating columns beyond the desired point. To adjust for lower boiler pressures, by providing for a greater initial content of water in the volume chamber, a longer tube 28 may be substituted for that previously in place. However, I need not necessarily make these adjustments by either cutting off a tube which is too long or substituting a longer one for one that is too short, but I may make the 130

same tube adjustable for length in either direction within certain limits by making it telescopic in a well understood manner.

The mode of operation of the indicator 5 will be readily understood without detailed explanation. It is sufficient to say that the columns rise in the tubes 4 and 5 respectively to relatively different heights in proportion as the column of water in the pipe line 10 which is connected to the one tube rises to a greater height than the present boiler level, the head of which is transmitted through the other pipe line to the other indicating tube. 29 represents a float, which 15 is provided in the inner tube, and is supported by the column of water therein in order more strikingly to show the height of the column therein.

The cock 30, shown in Fig. 3, is provided 20 to drain the volume chamber when it becomes necessary to withdraw all water therefrom.

It is to be remembered that I do not limit 25 my protection entirely to an instrument in which one of the tubes is inside of the other. Essentially these connected tubes form an inverted U-tube differential manometer, and the principles embodied in the device heretofore described at length can equally well 30 be applied to such a manometer, in which the legs are side by side, as to the specific type here shown. Likewise it is to be remembered that the description of use is in this 35 specification simply to explain the nature of the invention, and is not a limitation of its utility or scope. I claim as my invention all the novel features of the instrument itself, whatever the use may be to which it is put, and whether that use is for indicating 40 the level of water in a steam boiler or the level of any other liquid in a tank under the pressure of its own vapor or any other gaseous pressure, and whether the indicating liquid in the tubes is water or a different 45 liquid.

What I claim and desire to secure by Letters Patent is:

1. The combination with an indicator 50 having two legs connected at their upper ends, of a volume chamber connected to one of the legs of said indicator and adapted to contain air to be displaced into the indicator by flow thereto of liquid under pressure.

2. An indicator for measuring the level 55 of liquid in a container with reference to a fixed level, comprising essentially an inverted U-tube the legs of which are in communication with one another at their upper ends, means for connecting pipe lines containing liquid under pressure to the respective legs of said U-tube, and a volume chamber interposed between the connection of one 60 of said pipe lines with one of said legs.

3. A liquid level indicator, comprising 65 inner and outer indicating tubes in com-

munication at their upper ends and the outer tube being hermetically sealed at its upper end, liquid-containing pipe lines one of which is in connection with the lower end of said inner tube, and a volume chamber connected with the other pipe line and with the bottom of said outer tube and containing a quantity of gas adapted to be displaced into and compressed in said tube under inflow thereto of liquid under pressure. 70

4. A liquid level indicator, comprising inner and outer indicating tubes in communication at their upper ends and the outer tube being hermetically sealed at its upper end, liquid-containing pipe lines one of 80 which is in connection with the lower end of said inner tube, a volume chamber connected at its top with the bottom of the outer tube and being sealed at its bottom, and a tube from the other pipe line rising into 85 said chamber above the bottom thereof and adapted to serve as an overflow for water placed in the chamber prior to putting the indicator into action.

5. A liquid level indicator, comprising 90 inner and outer indicating tubes in communication at their upper ends and the outer tube being hermetically sealed at its upper end, liquid containing pipe lines one of which is in connection with the lower end of 95 said inner tube, a volume chamber connected at its top with the bottom of the outer tube and being sealed at its bottom, and a tube from the other pipe line rising into said chamber above the bottom thereof and 100 adapted to serve as an overflow for water placed in the chamber prior to putting the indicator into action, said last-named tube being adjustable in length whereby to regulate the proportion of the chamber then to 105 contain liquid.

6. An indicator instrument, comprising 110 the combination with conduits adapted to contain liquid under pressure, of a chamber, a tube entering said chamber from one of the conduits and rising to a height between the top and bottom thereof, an inverted U-tube indicator having one of its legs connected to the top of said chamber, and connecting means between the other leg of the 115 indicator and the other conduit.

7. A liquid level indicator for showing the fluctuating height of liquid in a boiler or other container at a distance therefrom, comprising 120 an indicator instrument having two legs in communication with one another at or near their upper ends and adapted to contain entrapped gas in their communicating upper parts, and pipe connections for leading water or other liquid from a boiler or similar container to one of said legs and from a liquid column of constant height to the other of said legs respectively, the liquid in both the container and the column of constant height being under the same elastic 125 pressure. 130

fluid pressure, distinguished by a volume chamber interposed between the bottom of one of said legs and the pipe connection running to that leg and adapted to contain gas 5 prior to the admission of the liquid under pressure to the indicator instrument, which gas, being displaced into said instrument

and compressed therein, prevents rise of the liquid to an objectionable height in the legs of the instrument.

10

In testimony whereof I have affixed my signature.

HARRY S. PARKS.
